Application October 30, 1936, Serial No. 108,318

9 Claims. (Cl. 34—48)

The present application is, in part, a division of our co-pending application Serial No. 691,522, filed the 29th day of September, 1933, United States Letters Patent No. 2,109,469. In said co-pending application there is shown, described and claimed a method and apparatus for treating fabric in long strips, or in continuous lengths, for the purpose of subjecting the fabric to different operations such as chemical treatments, mercerizing, increasing or decreasing of gloss, drying, finishing, and various other co-related steps, and while the process and apparatus of that application may be used for various kinds of fabrics, it may be successfully used in handling tubular, knitted goods, especially rayon, which latter is very sensitive and subject to impairment if the process does not protect the fabric against injury.

The present case is intended to cover the method of drying fabric, whether of knitted, tubular goods, or other fabrics, although certain features of the machine and method are especially designed to successfully treat tubular knitted goods which are more difficult to treat than woven and other kinds of fabrics. The present case is intended to cover a method and apparatus for drying fabric in any lengths and for maintaining the desired condition in the fabric while it is undergoing the drying operation in a drying chamber, and it is especially intended to control the movement of different portions of the fabric in the drying chamber according to the condition of the fabric at different portions thereof throughout the drying chamber and to control the propulsion of the fabric by automatic means which are themselves controlled by the tautness or looseness of the fabric at different places in the drying chamber. By controlling the movement of the fabric more or less locally in the different portions of the chamber, it is possible to avoid on the one hand too much tension in the fabric, and on the other hand to prevent excess local accumulation of the fabric beyond that desired.

Some fabrics, in the course of treatment, may require a slight tension or slight tautness while being subjected to the current of heated air for extracting moisture, whereas in other cases it is desirable to maintain a slight looseness in the fabric, and with the present apparatus and under the present method accurate control may be accomplished in a manner to meet all conditions for treatment of fabrics of different character.

In the handling of knitted, tubular fabric, the operation is especially delicate because such fabrics are made either of a single yarn or a very limited number of yarns constructed, as is well

known, in a series of interlocking loops, and such fabrics, when stretched lengthwise, have a tendency to draw in or become narrow unless restrained; and, conversely, when such fabrics are stretched or distended laterally they have a tendency to shorten in length unless restrained, and because of these characteristics it is necessary to control the movement or propulsion of the fabric, especially where there are a great many runs of superposed lengths in the drying chamber, by sensitive and delicate means which will on the one hand propel the fabric without creating any undue local stresses and at the same time prevent excessive accumulation of the fabric in its course of travel.

Under the present method and with the present apparatus the control is automatic and is effected through the condition of the fabric itself. By providing a multiple of controls disposed in the manner hereinafter described, each run of fabric or several adjacent runs of fabric may be independently controlled so that if the fabric should tend to tighten locally the condition may be remedied locally, and likewise if there is a local accumulation of fabric it may be taken up locally or the propulsion of the fabric may be modified to avoid excessive local accumulation.

Under the present method and apparatus all of these conditions may be successively met so that the fabric, after undergoing the complete drying operation, may be brought out of the drying chamber, either completely dry or with any desired percentage of moisture therein, and in the case of knitted, tubular fabrics, it is possible to deliver the fabric from the apparatus having a uniform width and having a given length per pound and treated uniformly throughout the length of the fabric.

Another object of our invention is to provide an equalizer for automatically controlling the fabric to cause it to move in a straight line through the drying apparatus and to prevent it from shifting laterally to an undesirable degree on the propelling rollers so that the median line of the fabric will travel substantially in a straight line while passing through the drying chamber. While this branch of our invention may be used on other types of machines for handling long strips of fabric, it is especially advantageous in the present machine to maintain the median line of the fabric in a straight line. Where the fabric, in passing through the drying chamber, is caused to travel in a multiplicity of superposed runs, we prefer to provide a rectifying device adjacent each propelling roller, or approximately one for each

second run of the fabric in the drying chamber. Each rectifying device is automatic in the sense that it is operated and controlled by the fabric itself, and if the fabric has a tendency to shift laterally adjacent a propelling roller, the rectifier automatically and gently restores the fabric to its correct course by producing a counterlead.

The present rectifier, in addition to maintaining the fabric in a straight line, also serves to remove wrinkles or creases which tend to form where fabric is passed reversely around a number of rollers. The present rectifier is simple in construction and very inexpensive to make, which permits a number of them to be used in a single drying chamber. The rectifiers produce rapid rectification of the course of travel of the fabric when the latter begins to leave the correct median line.

The present invention also involves novel means for driving the various propelling rollers which propel the fabric, together with means controlled automatically by the looseness or tautness of the fabric itself, for modifying the action of the driving means and the various fabric propelling rollers, and while we have shown in the present case a belt arrangement for driving the various fabric propelling rollers, it is to be understood that if desired the clutch device shown in our Patent No. 2,109,469, and also shown in our co-pending application Serial No. 160,980, may be used for operating the fabric propelling rollers within the scope of the method described herein, and within the scope of the broader claims on the apparatus. The particular form of drive shown and described herein is itself covered in the aforesaid pending application Serial No. 160,980. Any other form of drive may be used.

Different fabrics stretch differently due to their different weights per yard, to the differences in their structure, and to the moisture content, and the present apparatus is adapted to handle all fabrics under all conditions and to control or limit the longitudinal stretch of any kind of fabric and at the same time propelling the fabric through the drying chamber.

Other features and advantages of our invention will be set forth in detail in the following detailed description of our invention.

In the drawings forming part of this application:

Figure 1 is a side elevation of an apparatus embodying our invention in a preferred form,

Figure 2 is a plan view thereof,

Figure 3 is a sectional view taken on the line 55 3—3 of Figure 2,

Figure 4 is an enlarged elevation of the device for driving the fabric propelling rollers,

Figure 5 is a cross sectional view showing one of the fabric propelling rollers, and the automatic means for controlling its operation,

Figure 6 is a sectional view taken on the line 60 6—6 of Figure 5,

Figure 7 is a plan view of one of the rectifiers,

Figure 8 is an elevation of one of the rectifier 65 rollers with parts shown broken away to show the interior construction,

Figure 9 is a sectional view taken on the line 9—9 of Figure 7,

Figure 10 is a sectional view taken on the line 70 10—10 of Figure 7,

Figure 11 is a sectional view taken on the line 11—11 of Figure 7, and

Figure 12 is a perspective view of one of the fabric propelling rollers, the return guide rollers, 75 and one of the rectifying devices.

Figure 13 is a detailed sectional view of the air trap for preventing the heated air from passing through the horizontal dividing walls.

The heating chamber is preferably constructed of such shape and proportions as to provide for 5 a number of long horizontal runs of the fabric, although we do not wish to exclude from the scope of our invention a chamber in which the fabric is disposed in long vertical runs. In the drawings we have shown the drying chamber as consisting 10 of a bottom wall 1, a top wall 2 an end wall 3, an opposite end wall 4 together with side walls 5 all disposed in substantially rectangular formation, and these walls are preferably made of metal to avoid fire hazard. The chamber provided by 15 this structure is subdivided in the following manner:

First, there is preferably a wall 6 spaced from the end wall 4 to provide a vertical air flue 7 to 20 permit passage of air from one horizontal compartment to the other in the manner and for the purpose hereinafter set forth. There is a horizontal wall 8 or baffle extending from the vertical wall 6 toward the right in Figure 3, with its right hand end terminating a distance from the opposite end wall 3 so that the upper part of the housing is divided off into a flue or horizontal chamber which is a subdivision of the entire drying chamber. The air enters the left hand end of the compartment 9 and passes through the aero- 25 fins or air heating units 10 which are heated and which impart their heat to the air entering the compartment 9.

The air travels from left to right in this compartment and at the end of the baffle or horizontal wall 8 it passes around this wall and into the compartment 11 below this wall 8 where the air changes its direction and passes from right to left in the second compartment 11. This second compartment is defined partly by the horizontal 40 wall 8 just referred to and by the second horizontal wall 12 which at the right hand end in Figure 3 touches or is connected with the end wall 3 whereas the left hand end of this horizontal wall terminates against the frame 13 which surrounds 45 another aerofin or heating unit 14 which is preferably used as sort of a booster to add its heating effect to the air which has passed through the first compartment 9 to the second compartment 11.

The air which has travelled, therefore, through the horizontal compartment 11 passes the aerofin or heating unit 14 and this air is further heated and dried by the action of the aerofin or heating unit 14 and it changes its direction from left to 55 right in the third compartment 16, where it passes under the dividing wall 12. This third compartment is defined not only by the outer walls of the heating chamber but on the top by the horizontal wall 12 and on the bottom by another horizontal 60 wall 17 which extends at its left hand end from the wall 6 toward the right in Figure 3, and terminates short of the end wall 3 to leave a space for the air to pass from the third compartment 16 into a fourth horizontal compartment 18. This latter compartment is defined in part by the outer walls of the drying chamber and on the top by the wall 17 and on the bottom by another horizontal wall 19 which extends from the right hand end wall 3 to the left and in contact with the vertical wall 6.

At 20 we provide a screen to keep the fabric from being drawn out by the suction blower. From the compartment 18 the air is drawn out by means of a suction blower 22 operated by

the motor 23 and disposed outside the drying cabinet. We prefer to draw the air through the drying chamber by suction action in preference to a blowing action, although the latter will be operative, but to a less efficient degree.

We have shown the fifth or bottom compartment 24 extending lengthwise of the drying device and at one end there is an opening 25 in the wall 5 to allow external air to enter the chamber 10 24 at the right hand end in Figure 3, this air being outside air and therefore unheated until it reaches the aerofins, as shown by the arrows. The outside air which enters through the opening 25 passes from right to left in the compartment 24 and this 15 10 air passes through the opening in the lower portion of the vertical wall 6, then rises upwardly in the flue 1, passes from left to right through the upper portion of the vertical wall 6 the latter having openings for this purpose, and then the air 20 20 passes around and through the portions of the aerofins 10 where it is first subjected to the heat preparatory to its passage through the four horizontal compartments described above.

It will be understood that the drying chamber 25 may be divided into any desired number of horizontal compartments having any number of runs of fabric in each compartment through which the air and the fabric pass in succession and that while we have shown five different horizontal 30 30 compartments in the drawings, it will be understood that there may be a lesser or greater number than this. Where the cool outside air is allowed to pass first through the lowest compartment 24, this performs a conditioning operation 35 35 and serves to cool down the fabric after it is passed through the first four horizontal compartments and has been heated and dried, so that when the fabric emerges from the drying apparatus at the lower right hand end as indicated 40 40 by the arrow in Figure 3, it will not only have been dried but it will have been cooled down by the atmospheric air travelling through the lowest compartment.

If it is not desired to condition the fabric in 45 45 this manner then the damper 26 near the upper left hand corner of Figure 3 may be opened to allow the atmospheric air to enter through the opening 27 in the wall 4 to pass directly through the aerofin or heating unit 10 to enter the upper 50 50 horizontal compartment 9 directly instead of taking the air from the lowermost compartment. This allows the device to be used in either manner according to the nature of the fabric and the results to be accomplished.

55 There are horizontal rollers 28 arranged at relatively close intervals for each run of the fabric within the drying chamber, which rollers act as local supports for the moving fabric at different places intermediate the propelling 60 60 rollers. The spacing of the roller 28 next to each propelling roller is preferably greater than the spacing between consecutive rollers 28, so that a loop in the strip of fabric will tend to form where each controlling roller 60 engages the strip.

65 The fabric taken from any other machine or apparatus, such as the apparatus designated A in our said co-pending application Serial No. 691,522, in flat condition, enters the drying chamber at the upper right hand corner in Figure 3, 70 through the slot 29, and it then passes partly around the first propelling roller 30 which extends horizontally across the upper portion of the first horizontal compartment 9.

From there, the fabric passes over the first row of supporting rollers 28 and it then passes

through the first rectifying device 31 adjacent the left hand end in Figure 3, and it then passes partly around the second driving or propelling roller 32 whereupon the fabric is reversed in direction and passes from left to right in the second substantially horizontal run 33. Here it passes over a second row of rollers 28 to a point near the right hand end of the drying chamber and preferably above the right hand end of the baffle wall 8. At this location the fabric travels 10 10 partly around a roller 30 and is then again changed in direction so that it passes from this roller from right to left in what may be called the third run 34 within the upper compartment 9.

When it reaches the left hand end of this compartment the fabric passes around a second rectifier 31 and thence partly around the second propelling roller 32. It is then changed in direction and travels from left to right to form a fourth run 35 in the upper compartment, travelling over the fourth row of rollers 28. When the fabric reaches the right hand end of the baffle plate 8 it passes partly around a propelling roller 30 and its direction is again reversed so that the fabric passes from right to left, this time 20 20 forming the upper run 36 below the baffle wall 8. The fabric at the left hand end of the compartment 11 travels around a propelling roller 32, is again reversed in direction, travelling from left to right, and at the right hand end of this compartment it travels through a rectifier 31 and partly around another driving roller 30. This action is repeated in each succeeding compartment so that in each of the second, third, fourth and fifth compartments there are preferably 35 35 three runs of fabric, with suitable propelling rollers for driving and reversing the direction of the fabric, disposed in the several compartments and idlers for assisting in the support of the fabric.

40 From the last compartment the fabric passes out through the slot 37 between the guide rollers 38 partly around the guide roller 39 and then the fabric may be delivered to a finishing machine or apparatus or it may be wound into a roll or 45 otherwise disposed of.

The several arrows in Figure 3 indicate the direction of flow of the air current in the preferred arrangement. It will be apparent that during some of the runs of the fabric in the 50 horizontal chambers it is travelling with the air current, while in other runs it is travelling counter to the air currents. The general travel of the fabric while shown as being with the flow of air in Figure 3, that is to say, the fabric passes 55 55 successively from the upper to the next lower compartment, etc., and out of the lower compartment, and while the heated air first enters the upper compartment and then is delivered from the fourth compartment, it will be apparent 60 60 that the flow of heated air may be reversed so that the general travel of the air will be counter to that of the fabric. The heated air may be caused to flow in the reverse direction if desired.

65 Operating as illustrated in the drawings, the hottest air strikes the fabric when it has its greatest moisture, which is a desirable condition for many kinds of fabrics.

As stated above, the slip clutch devices illustrated in our said co-pending application Serial No. 691,522, may be used for operating the fabric drive rollers in the present apparatus, but herein we have shown a modified form of drive which has certain advantages. In the exterior view of the drying device, as shown in Figure 1, 70 70 75

we have illustrated a driving belt 40 which is endless and which is shown as operating in two vertical runs, the belt passing around the driving pulley 41 which in this case is preferably near the top of the machine, and passing around an idler roller 42 near the bottom of the machine, and the pulley 41 is driven from any suitable source of power being applied to the shaft 43 which carries the pulley 41.

10 The belt 40 may be of rubber or rubber composition, and it is preferably somewhat thick. One vertical run of this belt engages against the peripheries of a number of pulleys 44 arranged in a vertical row, each such pulley being fixed on the end of the shaft 45 of each fabric propelling roller 32, the shaft projecting through the vertical wall of the drying chamber so that the pulleys 44 are arranged on these shafts at the exterior of the drying chamber, it being understood, of course, that the belt 40 and its several pulleys are also mounted on the exterior of the drying chamber adjacent one end thereof. Near each pulley 44 there is mounted upon a bracket 47 (in Figure 4) a stud 48^b which forms a pivot 25 for the lever arm 48^a. Intermediate its ends each of these lever arms has mounted upon it a stud 49 on which an idler, presser roller 50 is freely revolvable.

It will be noted that the center of the stud 49 which is the axis of the roller 50 is slightly below the axis of the shaft 45 on which the pulley 44 is mounted, so that when the lever arm 48^a is moved to the right in Figure 4, the roller 50 presses an adjacent portion of the driving belt 40 against the periphery of the pulley 44 and that it causes a bending of the belt to wrap it slightly around the pulley 44 in order to provide sufficient traction as between the belt and the pulley to cause the latter to be driven by the belt at such 40 times as the pressure roller 50 is pressing the belt against the pulley.

The lower end of each lever arm 48^a has a hub 51 with a threaded bore, and there extends through this hub 51 a threaded adjusting sleeve 52. The hollow threaded adjusting sleeve 52 has inserted through it a long connection shown in the form of a wire 53 which is held in place by a collar 54 and set screw 54^a, the wire 53 being a loose fit through the hollow adjusting sleeve 52. The compression spring 54^b is a loose fit over the wire 53 and is held in place by the collar 54 at one side and the sleeve 52 on the other side. Any pull of the wire 53 from left to right would result in compressing the spring 54^b, applying 55 a gradually increased pressure against the sleeve 52 which is transmitted up through the lever 48^a until this pressure is brought to bear on the belt 40 against the pulley 44 by a pressing action of the roller 50. The effective length of the wire 53 may be adjusted by turning the threaded sleeve 52 in whatever direction may be desired until the proper effective length of wire 53 has been determined, after which the threaded sleeve 52 may be locked into place by the lock nut 52^a.

65 The wire 53, there being one of these wires to each lever 48^a, has its end opposite the threaded sleeve 52 passed through a pivot 55 and fastened to the pivot 55 by a set screw 56^a. The pivot 55 is inserted in the arm 56 of a lever 65 which is on the exterior of the drier and is fastened on a shaft 57 by a set screw 57^a, the shaft 57 extending through the side wall of the drying chamber.

70 Within the drying chamber this shaft carries a pair of parallel lever arms 58 shown in Figures 75 5 and 6, and there is connected between the

bosses 59 on the free ends of these arms a roller 60 extending crosswise of the drying chamber, and which roller is adapted to engage with the fabric in the manner hereinafter set forth to feel the fabric and to move into different positions in accordance with the tautness or looseness of the fabric where the roller engages. This roller is preferably covered with a fabric covering 61 so that it will not injure the delicate surface of the fabric which is being treated.

10 We have shown the roller as of light construction and consisting of a light cylindrical shell 62 having end pieces 63 secured therein; and these end pieces form bearings on the small rod 64 which forms the shaft of the roller and which is itself mounted in the bosses 59 carried by the lever arms 58.

15 There is shown a counter weight arm 65 fixed upon the shaft 57 on the portion which projects to the exterior of the drying chamber; and this arm has a series of notches 66 on its upper edge to receive a tooth 67 on an adjustable counter-weight 68 which is adjustable to the various positions along the arm 65 for the purpose of counter-balancing a portion of the weight of the arms 58 20 and the roller 60 so that this roller will press very lightly against the fabric, it being intended that the pressure shall only be sufficient to cause the roller to follow the adjacent portion of the fabric as it becomes taut or loose and to offer 30 substantially negligible resistance to the movement of the fabric. The weight 68 may therefore be adjusted along the lever arm 65 so that the roller 60 may remain in contact with the fabric but engage it lightly for the above reasons.

35 Each propelling roller is shown as constructed of a light hollow cylinder 69 which is covered on its exterior with a fabric 70 which is desirably made of velvet or plush, or other suitable material, this covering being held at one end of the 40 roller by a ring 71 which presses the material into a peripheral groove in the cylinder; and at its other end it passes around the flange 72 on the flange member 73 on which one end of the cylinder 69 is mounted. The coiled spring 74 expanding 45 against the portion of the covering fabric 70 on the under side of the flange 72 holds this end in place. The flange member 73 is provided with a hub 75 which is mounted on the shaft 45 and is secured thereto by the set screw 76 so that the 50 roller is caused to turn with the shaft 45.

55 At the right hand end of the apparatus as viewed in Figures 1 to 4 inclusive, there is a second propelling belt 40' disposed to operate in vertical runs, and this belt performs the same functions regarding the fabric propelling rollers at the right hand end of the machine as the belt 40 60 performs at the left hand end of the apparatus, and the parts associated therewith correspond with those associated with the belt 40 65 and they will be similarly numbered, but with prime numbers to distinguish them from the parts associated with the belt 40 and to show, at the same time, which parts associated with the belts are similar in function.

65 It will be observed especially from Figure 1, that in the preferred arrangement the wires 53 which are connected at the left hand end with the short lever arms 56 extend toward the right of the apparatus and slightly inclined downwardly, 70 so that these wires engage with lever arms 48 of the propelling rollers at the right hand end of the machine and, conversely, the wires 53 which are connected with the short arms 56 on the right hand end of the apparatus slant downwardly 75

and are connected with the lever arms 48^a at the left hand end of the apparatus. This arrangement causes the control rollers 60 to directly effect the operation of a propelling roller at the opposite end of the apparatus in order to slow down the propulsion of the fabric as it becomes taut at the right hand side of the apparatus and conversely, to slow down the fabric at the right hand end of the apparatus if the controlling roller 60 at the left hand end of the apparatus is caused to move by a local tightening of the fabric at that end.

There are local guide rollers 78 in Fig. 3, engaging the fabric just after it leaves one of the rollers 30, 32, which idlers serve to cause the fabric to engage a greater portion of the circumference of the rollers 30, 32, in order to secure the desired traction between the propelling rollers and the fabric.

20 The rectifying devices which are shown in Figures 7 to 12 are placed at advantageous points in the drier, preferably engaging the fabric immediately in advance of the propelling rollers 30, 32.

25 The strip of material being driven by and running over the rollers 30, 32 has a tendency to run off to one side or the other of the roller, unless there is something to hold the material properly centered and aligned, especially if the material 30 to be a soft texture, such as a knitted fabric. Where there are superposed layers of the fabric, especially in moist condition, and the fabric changes in its direction of movement, it has been difficult to keep the fabric centralized on the 35 rollers and it has been difficult to eliminate creases and wrinkles in the strip of fabric.

We have shown a simple and inexpensive rectifier which automatically rectifies the course of travel of the fabric to counteract its tendency to 40 run off to one side or the other of the rollers and when such tendency arises the rectifier guides the fabric back into central position. There is shown in Figures 7 to 12 inclusive one of the rectifiers embodying part of our invention. 45 The roller 32 shown in Figures 7, 9 and 12 is one of the propelling rollers for propelling the strip of fabric through the drying chamber and a rectifying device is arranged just in advance of such roller and each roller 30.

50 There is shown a cross member 80 mounted in the uprights 81 of the frame of the drying chamber and within the heating chamber in a stationary position over the propelling roller 32. This cross piece at its middle portion supports an 55 arm 82 which extends forwardly of the propelling roller 32 and above it. At the end of this arm 82 there is a pivot bolt 83 which forms a support for an oscillating frame 84 which is adapted to oscillate in a horizontal plane and to 60 a limited extent around the bolt 83; and in order to allow this frame to move with least resistance we prefer to provide ball bearings 85 interposed around the bolt 83 and on which the frame 84 oscillates.

65 The swing of the rectifier is limited by adjustable screws 83^a which are threaded into the ears 83^b on the member 84 and which strike the bar 82.

The oscillating frame carries the traction rollers 70 which automatically maintain the fabric centralized and preferably these rollers are constructed as follows: There are shown three rollers 86, 87, 88 and extending parallel to each other, and each roller consisting of a section 89 on the left side of the frame 82, and a section

90 on the right side of the frame 82, and preferably these two sections of each roller diverge in relation to each other as shown in Figure 7. The two sections of each roller are shown on an angular shaft 91 which is secured at its end to the brackets 92 which are mounted on the oscillating frame 84. The sections of the rollers are shown as composed of thin cylindrical walls 93 having blocks 94 disposed inside the tubular member and adjacent opposite ends thereof, and these blocks 10 have their bearings on the shafts 91. The sleeves 95 serve as spacers to maintain the roller sections in proper positions on the shaft.

The cylinders 93 are preferably covered with a fabric 96 which may be velvet or plush in order 15 to have sufficient traction for the fabric to revolve the several rollers 86, 87, 88 which are in fact idlers. Preferably, one of the roller sections, for instance the section on the right of Figure 8, has a plug 97 in the end of the cylinder 20 93 which plug projects beyond the end of the cylinder and into the open end of the cylinder 93 of the other roller section. This plug is shaped as shown at 98 to provide a member for the travelling fabric to rest against and to prevent 25 the fabric from piling up against the edge of either roller section when it shifts from one side to the other of the exact central line.

30 Preferably, all three rollers 86, 87, 88 are constructed alike, so that the above description applies to each of them. Of course, it will be understood that two rollers may be used, or more than three rollers, but we have found that three rollers in each rectifier will perform all of the functions desired. We have shown extensions or ears 35 99 on the frame 84 with rods 100 connected thereto and extending downwardly between adjacent roller sections to prevent either edge of the travelling fabric from becoming entangled with the ends of the rectifier rollers. 40

The device shown in Figure 13 is to prevent the heated air from passing through the dividing walls, such as 12 and 19, where the rollers 32 are located. It consists of the plate 102 having turned down ends to which the pivot rod 103 is 45 attached and on which the plate 102 pivots. The roller 101 is attached to the turned down ends of the plate, the periphery of this roller moving close from one edge of the plate 102 and resting also on the roller 32 to close the aperture in the 50 plate 17 or 19, as the case may be, where the roller 32 is located, to prevent the heated air from passing through the opening in the plate 17 and 19. 55

Operation

When the strip of fabric to be treated has been threaded through the apparatus, it will appear as shown in Figure 3; that is to say, the fabric coming from another machine or apparatus leads through the slot 29 in the upper right hand corner of the drying chamber and from there the fabric passes from right to left through the upper longitudinal compartment 9; thence through one of the rectifiers; around the left hand feed roller 32, after which the fabric passes from left to right, thence around a roller 30 and from there the fabric passes from right to left on the third run and at the left hand end of the apparatus it again passes through a rectifier and around a feed roller and from there the fabric 70 passes again from left to right to the right hand end of the baffle 8 whereupon it passes around another feed roller and thence back under the baffle 8.

In this manner the fabric passes back and forth

in several runs in each horizontal compartment throughout the four compartments, and it then passes into the lower or fifth compartment where it also travels back and forth in the several horizontal runs and then emerges through the slot 38 at which time the fabric will have been completely dried if that is the object to be attained, or the moisture content may have been reduced to any desired degree. The suction blower 22 will exert a suction action in the compartment 101 and this will draw the heated air from the upper horizontal compartment through the one next to it, and thence through the one next below it, etc. until the air which has given up a large percentage of its heat to the fabric and which has extracted moisture from the fabric will be exhausted into the atmosphere by the blower.

While the heated air is travelling in succession through the several horizontal compartments to heat the fabric it extracts moisture therefrom and the operation may be controlled by the speed of travel of the fabric through the drying chamber and by the operation of the aerofins and if uniformity in both of these factors is maintained the condition of the fabric will be uniform when it is delivered from the apparatus.

Different horizontal runs of the fabric within the drying chamber are driven by the propelling rollers 30, 32. The controlling rollers 60 which control the operation of the fabric propelling rollers are so disposed in the drying chamber that they rest downwardly on the top surface of the fabric as shown in Figure 3. One of these controlling or feeler rollers is shown as disposed to engage the fabric near each propelling roller, i. e., to engage the fabric just after leaving the propelling roller. Each of the control rollers rests by very light pressure against the fabric and if there is too much slack in the fabric where one of these rollers rests upon it the roller will move downwardly in following the fabric and this will cause the lever 58, 65 to rock slightly and the short arm 56 of lever 65 will draw on one of the wires 53 and this motion will be transmitted through the wire to one of the levers 48^a or one of the levers 48' causing the latter to rock slightly.

50 This will cause its roller 50, or 50' to press against either the driving belt 40 or the driving belt 40' to create driving friction of one of these belts against one of the pulleys 44 or 44' and this frictional engagement between the belt and the pulley will set the corresponding travelling propelling roller 30 or 32 into operation, or increase its operation as the belt 40 or 40' is wrapped slightly around the pulley 44 or 44'. This will cause the fabric to be driven by one of the propelling rollers to remove part or all of the slack in that part of the fabric where the controlling roller 60 is testing the fabric for its slackness. As the slack in this part of the fabric is gradually taken up by the propulsion set up by the operation of one of the driving rollers, the controlling roller 60 is lifted by the fabric itself.

When this occurs, the pull on one of the wires 53 as described above is released and this releases the pressure of the corresponding roller 50 or 50' against either the belt 40 or the belt 40' as the case may be, and this will reduce or terminate the driving action of the belt upon the particular pulley 44, 44' so that the shaft on which this particular pulley is mounted and the fabric propelling roller on that shaft may slow down or

come to a stop and remain quiescent until the same controlling roller again moves downwardly as a result of accumulation of slack in the fabric where that particular controlling roller engages it.

While to some extent the belt 40 or the belt 40' 5 may drive one of the pulleys 44, 44' while the pressure of the roller 50 or 50' is being applied or released, the device will be effective even if it works on the start and stop principle, that is to 10 say, even if the pulley 44 or 44' is only driven when the roller 50 or 50' is pressed against the drive belt 40 or 40' under the full action of a controlling roller 60.

Different portions of the total strip of fabric 15 which lie within the drying chamber at one time will be tested by the controlling rollers 60 at different local positions, according to the disposition of these rollers, such as is shown in the drawings, so that different fabric driving rollers in the dry- 20 ing chamber may be performing differently from each other; that is to say, at a moment when one is temporarily idle another drive roller may be operating because control of the propulsion of the fabric is divided up amongst the several pro- 25 pelling devices and they are controlled locally by their respective controlling rollers.

It will not suffice to operate all of the propelling rollers at the same speed or to operate them all at the same definite ratio even with different driving 30 parts moving at different speeds to others because the fabric is undergoing variations in tightness and looseness throughout different portions of the drying chamber and the driving of the fabric locally must conform to the local condition of 35 the fabric, which is possible in the present apparatus. The fabric is undergoing some change in length due to the change of the moisture content in the fabric in the drying chamber, and it is undergoing change of weight due to loss of 40 moisture.

In most cases it is desirable, especially where knitted fabric is being handled, to avoid excessive tension or tautness in the fabric while it is being propelled through the drying chamber or, in other words, it is desired to keep the fabric loose, but nevertheless to avoid having it pile up at any point of its travel, due to excessive looseness. Through the mechanism described herein it is possible to have all parts of the fabric loose or 50 without material longitudinal tension and at the same time to prevent the fabric from piling up at any point, due to excessive looseness.

Under the method described herein, we automatically control the drive of the fabric locally 55 or at various points throughout the drying chamber with means such as the feeler rollers which are controlled by the fabric itself and which bring about local propulsion of the fabric in accordance with these automatic feelers.

The strip of fabric just before it approaches one of the propelling rollers 30 or 32 passes under the first roller 88 of a rectifier, thence partly over the second roller 87 and thence partly under the third roller 86 of the rectifier from which it 65 passes directly onto the propelling roller. The traction of the fabric on the several rollers of the rectifier causes the latter rollers to revolve as they are in the nature of idlers. The rollers, by reason of their formation in divergent sections, 70 will cause any creases or wrinkles in the fabric to be worked off in opposite directions from the median line of the fabric to the edges so that when the fabric reaches the propelling roller 30 or 32 any wrinkles or creases will have been

smoothed out and caused to pass off the side edges of the fabric. The bolt 83 which is the pivotal point of the frame 84 is preferably in the center line of the correct path of travel of the fabric or in line with the middle of the fabric propelling roller 30 or 32.

The fabric in flat form, whether of a single thickness or a flattened tube, will travel in a horizontal plane and will reach the rectifier 10 from some previous roller or guiding means or from any other source such as a drive roller 30 or 32 in Figure 1. There will be sufficient traction between the rollers 86, 87, 88 and the fabric to cause the former to be revolved by the fabric.

15 The function of the rectifier is to keep the travelling strip of fabric centralized in relation to the fabric propellers 30 and 32. If, while the fabric is travelling through the rectifier, it for any reason develops a tendency to lead toward 20 the right on a roller 30 or 32 as viewed in Figure 7, the fabric will travel on the rectifier rollers toward the right, and when this takes place there will be more fabric engaging the rectifier roller sections to the right of the pivotal point 83 and this will cause the rectifier to turn diagonally toward the left in Figure 7 or to swing anti-clockwise; and the rectifier will thereupon immediately develop a left lead in the travelling fabric. This left lead will overcome the previously developed right lead of the fabric or, in other words, the rectifier will automatically equalize the fabric by leading it back toward the correct position.

When this counter lead develops, and starts to bring the fabric back to its correct position, the 35 rectifier will also move from its diagonal position back to its central position so that by the time the fabric has been corrected in relation to a roller 30 or 32 the rectifier itself will have been brought back to the neutral or straight position 40 at right angles to the correct travel of the fabric, as indicated in Figure 7. The lateral lead caused by the rectifier is therefore brought to an end when the fabric has been brought back to its correct path.

45 The rectifying action is not sudden but it takes place gradually as is necessary with a wide, soft fabric. If the pivotal screw 83 is arranged directly over the frame 84 the rectifying action will be much slower and more gradual, whereas 50 if this pivotal point is arranged ahead of the frame 84 as shown in Figure 7, there is a greater swing to the rectifier and therefore the rectifying action is quicker. It is preferable to arrange one of these rectifiers adjacent each fabric propelling roller.

55 If the fabric near the rectifier tends to develop a left lead the opposite action will take place to that described above, and the rectifier will provide a right counter lead and bring the fabric back to its correct position. The rectifier operates on substantially the full width of the fabric rather than locally, and instead of creating wrinkles in the strip it irons and smooths them out. A rectifying device may be placed to act on 60 the fabric before it passes into the drying chamber to insure accurate entry of the fabric into the drying chamber. Other rectifiers, independent of each other, and all automatic in their operation are preferably used in the drying chamber as 65 shown, to insure uniform directional progress of the fabric.

70 While we have illustrated and described a certain form in which the invention may be embodied, we are aware that many modifications may be made therein by persons skilled in the art

without departing from the scope of the invention as expressed in the claims. Therefore we do not wish to be limited to the particular form shown or to the details of construction thereof.

Having described our invention, what we claim 5 is:

1. Apparatus for continuously drying lengths of fabric which comprises a vertical series of horizontal drying compartments, means for conveying the fabric through the compartments in sequence, an air inlet adjacent the fabric discharge end of the last compartment of the series, an air passage connecting the opposite end of said last compartment with an end of the first compartment of the series, air passages connecting 10 the ends of the compartments except the last compartment in series forming a continuous passage for the air through said compartments, and an outlet for the air from the next to the last compartment of the series. 15

2. Apparatus for continuously drying lengths of fabric which comprises a plurality of communicating drying compartments, a fabric entrance in the first of the compartments and a fabric exit in the last of the compartments, fabric conveying mechanism within the compartments for conveying the fabric through the compartments successively from the entrance to the exit, an air passage connecting an end of each compartment with the adjacent end of the next 20 successive compartment, excepting the last compartment, a connecting air passage connecting the last compartment with the first compartment, heating means imparting heat to the air entering the first compartment, an air vent in the last 25 compartment admitting fresh air, an air exhaust vent in the next to the last compartment through which vitiated air is exhausted and a blower for driving air through the compartments and passages from one of said vents to the other. 30

3. Apparatus according to claim 2 in which there is an air vent in said connecting passage adapted to lead air into the air flow to the series of compartments. 40

4. The method of drying traveling lengths of 45 fabric comprising conveying the fabric in flat spread condition in a plurality of parallel runs in each of a series of communicating drying compartments, subjecting the fabric while in all but the last of said compartments to a heated current 50 of air entering the first of said compartments and moving through each compartment in the same general direction as the fabric, cooling the fabric in the final drying compartment by passing a fresh current of cool air through said compartment, heating the cool air leaving the last compartment and supplying the air to the first compartment and continuously maintaining a predetermined slackness in each parallel run of fabric throughout the drier by regulating the speed of 55 propulsion at the end of each run in accordance with the slackness of the fabric at the beginning of the run so that each run of fabric has a predetermined freedom to respond to the drying conditions to which it is subjected. 60

5. The method of drying as set forth in claim 4 in which the heated current of air is first maintained against further heating so that the temperature of the air at first decreases and then reheating said air current a predetermined 70 amount to raise its temperature within the safe temperature limit of the partially dried fabric and then permitting the temperature of the air to decrease as the air current further progresses along with the fabric. 65

6. Apparatus for continuously drying lengths of fabric which comprises a plurality of communicating drying compartments, a fabric entrance in the first of the compartments, and a fabric exit in the last of the compartments, fabric propelling means within the compartments comprising fabric driving rolls located at the ends of each compartment for conveying the fabric in spread flat form and in a plurality of superposed sinuous runs within each compartment and through the compartments successively from the entrance to the exit, a variable friction drive for each driving roll and a controlling roller riding on the fabric, control means for each variable friction drive operated by the controlling roller and automatically varying the friction drive in accordance with the slackness of the fabric, an air passage connecting an end of each compartment with the adjacent end of the next successive compartment, heating means imparting heat to the air entering the first compartment and air propelling means causing the heated air to flow

from one compartment to the next through the connecting air passage from the first of the compartments to the last of the compartments so that the fabric and air progress in the same sequence through said compartments. 5

7. Apparatus as set forth in claim 6 in which the fabric driving rolls at corresponding ends of the drying compartments are in vertical alignment adapted to be driven from a single source of power. 10

8. Apparatus as set forth in claim 6 which includes means for reheating the air a predetermined amount at a point intermediate the first and last drying compartment. 15

9. Apparatus as set forth in claim 6 having an inlet for the air entering the first compartment, said inlet being opposite the fabric entrance so that the initial run of said fabric is countercurrent to the direction of flow of the air. 20
